(57) **CLAIM**

The ornamental design for a convertible pallet, as shown and described.

DESCRIPTION

FIG. 1 is a top view of the pallet;

FIG. 2 is a side end view of the pallet, opposed sides being identical;

FIG. 3 is a front end view of the pallet, the rear end view being identical;

FIG. 4 is a perspective view of the convertible pallet; and, FIG. 5 is a perspective view of the design of FIG. 4 wherein wheels are shown in phantom in the four corners of the pallet.

The broken lines shown in FIG. 5 are for illustrative purposes only and form no part of the claimed design.
